CLAIM

The ornamental design for an assembled electronics housing, as shown and described.

DESCRIPTION

FIG. 1 is a top front perspective view of our assembled electronics housing;

FIG. 2 is a top rear perspective thereof;

FIG. 3 is a top view thereof;

FIG. 4 is a bottom view thereof;

FIG. 5 is a front side view thereof;

FIG. 6 is a rear side view thereof; and,

FIG. 7 is a side view thereof.

The right side view of the assembled electronics housing, as illustrated in FIG. 7 is a mirror image of the left side view of the assembled electronics housing.
